United States Patent

Des. 236,805

Patented Sept. 16, 1975

236,805

PACKAGE FOR ICE CREAM CONES OR THE LIKE

Paul Davis, Swampscott, and David Schneider, Lexington, Mass., and Paul Hollinger, Pikesville, Md., assignors to Sweetheart Plastics Inc., Wilmington, Mass.

Filed Jan. 31, 1974, Ser. No. 438,267

Term of patent 14 years

Int. Cl. D9—03

U.S. Cl. D9—183

FIG. 1

FIG. 2

FIG. 3

FIG. 4

FIG. 5

FIG. 1 is a top plan view of a package for ice cream cones or the like showing our new design, the bottom plan view being identical thereto;

FIG. 2 is a front elevational view;

FIG. 3 is a right end elevational view;

FIG. 4 is a left end elevational view; and

FIG. 5 is a reduced scale top plan view thereof shown in a fully opened position.

We claim:

The ornamental design for a package for ice cream cones or the like, as shown and described.
